CLAIM

The ornamental design for an inhaler, as shown and described.

DESCRIPTION

FIG. 1 is a top perspective view of an inhaler showing our new design;

FIG. 2 is a bottom perspective view thereof;

FIG. 3 is a top plan view thereof;

FIG. 4 is a front elevational view thereof;

FIG. 5 is a rear elevational view thereof;

FIG. 6 is a bottom plan view thereof; and,

FIG. 7 is a left side elevational view thereof, the right side elevational view being a mirror image thereof.

The broken lines in the figures depict portions of the inhaler which form no part of the claimed design.

The black areas in the figures depict portions of the inhaler having a contrasting surface appearance, such as contrasting color, including black.
